UNITED STATES PATENT OFFICE.

ARTHUR N. HOOD, OF NEWTON, MASSACHUSETTS, ASSIGNOR, BY MESNE ASSIGNMENTS,
TO SHAWMUT TIRE CO., A CORPORATION OF MASSACHUSETTS.

DESIGN FOR A RUBBER VEHICLE-TIRE.

41,497.

Specification for Design.

Patented June 20, 1911.

Application filed February 18, 1911. Serial No. 609,541. Term of patent 7 years.

To all whom it may concern:

Be it known that I, ARTHUR N. Hood, a citizen of the United States, residing at Newton, Massachusetts, have invented a new, original, and ornamental Design for Rubber Vehicle-Tires, of which the following is a specification, reference being had to the accompanying drawing, forming a part thereof.

In this drawing Figure 1 is a perspective

view of a tire showing my new design, and Fig. 2 is a plan of a portion of the tread.

I claim:

The ornamental design for a rubber vehicle tire herein shown.

ARTHUR N. HOOD.
